UNITED STATES PATENT OFFICE.

ROY L. BOWMAN, OF TOLEDO, OHIO.

AUTOMATIC BOWLING TOY.

1,323,003.

Specification of Letters Patent. Patented Nov. 25, 1919.

Application filed July 8, 1919. Serial No. 309,343.

To all whom it may concern:

Be it known that I, ROY L. BOWMAN, a citizen of the United States, residing at Toledo, in the county of Lucas and State 5 of Ohio, have invented certain new and useful Improvements in Automatic Bowling Toys, of which the following is a specification.

My invention relates to mechanical toys 10 and has particular reference to such a device wherein figures representing a bowler and pin setter are employed; and operate in a manner simulating the playing of a game of ten pins.

An important object of the invention is 15 to provide means whereby the bowler and pin setter are automatically operated by a series of balls, traveling down an inclined chute or trough, such balls being discharged from the hand of the bowler and thrown upon the alley, to strike the pins, and subsequently actuate the pin setter.

A further object of the invention is to 20 provide a toy of the above mentioned character, which is simple in construction, and entirely automatically operated by gravity acting upon the series of balls, thereby dispensing with the necessity of employing pulleys, belts, springs, etc.

Other objects and advantages of the 25 invention will be apparent during the course of the following description.

In the accompanying drawings forming 30 a part of this specification and in which like numerals are employed to designate like parts throughout the same,

Figure 1 is a perspective view of a mechanical toy embodying my invention,

Fig. 2 is a transverse vertical sectional view taken through the feeding chute or magazine, the same being taken on line 2—2 of Fig. 1, the ball ejector being in the lowered position,

Fig. 3 is a similar view showing the ball 45 ejector elevated,

Fig. 4 is a transverse sectional view through the device, immediately in front of the pin setter figure,

Fig. 5 is a longitudinal vertical sectional 50 view taken on line 5—5 of Fig. 2,

Fig. 6 is a horizontal section taken on line 6—6 of Fig. 5,

Fig. 7 is a similar view taken on line 7—7 55 of Fig. 5,

Fig. 8 is a transverse vertical sectional

view through the device, near the bowler figure, and looking rearwardly,

Fig. 9 is a front and side elevation of a vertical feed chute,

Fig. 10 is a side elevation of a figure,

Fig. 11 is an edge elevation of the same, parts being in section,

Fig. 12 is a side elevation of the leg support for the figures,

Fig. 13 is an edge elevation of the same,

Fig. 14 is a plan view of the same, and,

Fig. 15 is a longitudinal section through the ball operated lever.

In the drawings, wherein for the purpose of illustration is shown a preferred embodiment of my invention, the numeral 20 designates an alley, preferably formed of sheet metal which is bent to provide a depending supporting side 21, which is vertical, and has a vertical flange or rib 22 at its upper 70 end, projecting above the alley 20, and serving to prevent the balls from falling off of the alley. The alley 20 is preferably flat and inclined downwardly toward its forward end. Arranged at the opposite side of the 80 alley 20 is a plate or wall 22, which is arranged vertically and is secured thereto. This plate serves to support the alley 20 and projects above the same for a substantial distance. The vertical plate has the upper 85 portion of its material bent laterally for providing a ball trough or runway 23, which is inclined downwardly toward the rear end of the device. The trough 23 is provided with a diagonal strip 24, having 90 lugs 25, passed through openings or slots formed in the plate or support 22, thereby serving to reinforce and stiffen the trough or runway.

Arranged at the rear end of the alley 20, 95 and in proximity to the wall or support 22, is a vertical feed chute 26, held stationary to these parts by any suitable means. This vertical feed chute is provided upon its outer side with an opening or cutaway portion 27, see Fig. 3, which leads into the inclined trough 23. The opposite or inner side of the feed chute 26 has an inlet opening 28, which leads into an inclined ball receiving magazine 29. The magazine 29 is 100 connected with a support or plate 30 and the lower end of the magazine is adjacent the vertical chute 26, whereby the balls 31 contained therein will automatically gravitate into the vertical chute. The ball receiv- 110

ing magazine 29 may be formed by bending the upper end of the plate or support 30, but the invention is of course in no sense restricted to this feature.

5 Arranged to reciprocate vertically within the chute 26 is an ejector 32, having an upper inclined head 33, extending downwardly toward the trough or runway 23. When in the lowermost position, the ejector 10 32 has its head flush with the bottom of the magazine 29 and the lowermost ball 31 is then free to enter the vertical chute 26 and is supported by the ejector. When the 15 ejector is raised its outer side closes the opening 28 and prevents the next ball from entering the vertical chute, while the ejector elevates the ball thereon and finally discharges the same into the trough or runway 23.

20 The ejector 32 is carried by an upstanding shank 34, operating through an opening 35 in the alley 20. This shank is pivotally connected, as shown at 36 with a vertically swinging operating lever 37. The operating lever is pivoted to a support 38, at 39, the support 38 being preferably in the form of a tongue stamped from the material of the alley 20. The pivot 39 is arranged nearer the forward end of the lever 37, whereby the rear end of the lever constitutes the long arm of such lever. The rear end of the operating lever 37 is provided with a pocket 40, to receive the balls 31, such pocket having a downwardly bulging portion or depression 41, which serves to retain the ball within the pocket until the lever has been swung thereby to its lowermost position, the ball then automatically discharging from the pocket. This ball is 40 then fed into a transverse trough 42, serving to discharge the ball through an opening 43 in the wall 21, to the exterior thereof.

At its rear end, the alley 20 has its material bent for providing a transverse receptacle or chamber 44, having a discharge opening 45 formed in its bottom, preferably near its lower end, such bottom being preferably transversely inclined. The receptacle 44 has perpendicular side walls 46 45 and 47, the wall 47 extending upwardly to provide a stop 48, having a diagonal strip 49, to engage with an extension 20' of the alley 20. When in the upper position, the pocket 40 is arranged near and directly beneath the opening 45, to receive the ball therefrom.

Arranged in advance of the depressed receptacle 44, are longitudinal slots 50, formed in the alley 20, and receiving ten pins 51, pivotally supported upon transverse pivots 60 52, and carrying weights 53 at their lower ends, which return the same to the vertical position when moved therefrom by contact with the balls.

The numeral 54 designates a bowler figure 65 as a whole, comprising a leg support 55.

This leg support, as shown more clearly in Figs. 12, 13 and 14, is formed of a single section of sheet metal stamped to provide a transverse connection 56, having hips 57 secured thereto, carrying depending legs 58. 70 The legs 58 are provided at the feet with tongues 59, to enter the slots of the alley 20, which tongues may be bent back. An attaching arm 60 is also carried by one hip 57 and has a depending tongue 61, to engage 75 behind a strap 62. The legs may be suitably painted or decorated, as desired. The figure further comprises a body portion 62, which is hollow and receives the upper end 80 of the legs 40, and is pivoted thereon, at 63. This body portion embodies a weight 64 in the lower end of the coat tail upon the body portion, and serving to normally retain the body portion upright, this body portion remaining slightly tilted forwardly. The 85 body portion 62 carries a head 65, and arms 66 and 67. The arm 67 has a pocket 68, adapted to receive a ball from a lateral discharge spout 69 connected with the lower end of the chute or runway 23.

90 The numeral 70 designates a pin setter figure, as a whole, embodying a leg support 71, similar to the leg support 55, and held stationary by similar means. The body portion 72 of this figure is pivoted to the leg support 71, at 73. The body portion carries a head 74, and an arm 75, pivoted thereto at 76. This arm has pivotal connection with the pin 77, operating through a slot 78, Fig. 9, in the vertical chute 26. This pin is 100 connected with the ejector to move therewith. The body portion 72 is normally forwardly inclined, but when the arm 75 is elevated, this body portion is also thrown back or straightened, giving the appearance 105 as if the figure was engaged in returning the balls to the trough or runway 23.

The operation of the device is as follows:

110 The inclined magazine 29 is filled with the balls 31, and the lowermost ball will gravitate into the vertical chute 26 and is supported therein by the ejector 32, then occupying the lowermost position. The operator then places a ball 31 in the upper end of the runway or trough 23, and releases the same. This ball travels by gravity toward the lower end of the runway and discharges through the spout 69 into the pocket 68 of the arm 67. The weight of this ball now swings the body portion 62 of the 115 bowler forwardly and downwardly, the ball being thereby discharged upon the alley 20. This ball rolls toward the forward end of the alley, striking the ten pins 51, and discharging into the receptacle 44. The ball 120 next passes from this receptacle through the opening 45 and enters the pocket 40 of the lever 37, swinging the long arm of this lever downwardly. This moves the short arm of the lever upwardly, elevating the ejector 32, 125 130

which transfers the lowermost ball 31 supported by the ejector into the upper end of the runway 23. This ball will now pass downwardly through the runway and the 5 operation is repeated. It is thus seen that the device will be operated automatically, and that such operation is only limited by the number of balls employed. When the 10 ejector 32 is elevated, the body portion of the pin setter 70 is moved rearwardly or upwardly, and the arm 75 is given an upward movement, whereby it appears as if the pin setter is returning the ball to the runway 23.

15 It is to be understood that the form of my invention herewith shown and described is to be taken as a preferred example of the same, and that various changes in the shape, size, and arrangement of parts may be 20 sorted to without departing from the spirit of my invention, or the scope of the subjoined claims.

Having thus described my invention, I claim:

25 1. A game of the character described, comprising an alley, elements arranged upon the alley to be struck by a ball traveling longitudinally of the same, a bowler figure arranged near one end of the alley 30 and having a receptacle to receive a ball and adapted to discharge the same upon the alley, an inclined runway to receive the ball and discharge the same into the receptacle of the bowler figure, and means actuated by 35 the weight of the ball passing from the alley for feeding another ball into the runway.

2. A toy of the character described, comprising an alley, elements arranged upon the alley to be struck by a ball traveling longitudinally of the same, a bowler figure arranged near one end of the alley and having a receptacle to receive a ball and adapted to discharge the same upon the 40 alley, an inclined runway to receive the ball and discharge the same into the receptacle of the bowler figure, a magazine for receiving and holding a plurality of balls, means for transferring the balls from the magazine to the runway, and means actuated by 45 the weight of the ball passing from the alley for operating the transfer means.

3. A toy of the character described, comprising an alley, elements arranged upon the 50 alley to be struck by a ball traveling longitudinally of the same, a bowler figure arranged near one end of the alley and having a receptacle to receive a ball and adapted to discharge the same upon the alley, an 55 inclined runway to feed the ball to the receptacle of the bowler figure, a magazine for receiving and holding a plurality of balls, a chute receiving the balls from the magazine and extending to the runway, an 60 ejector operating within the chute, and 65

means operated by the ball fed upon the alley for operating the ejector.

4. A toy of the character described, comprising an alley, elements arranged upon the alley to be struck by a ball traveling 70 longitudinally of the same, a bowler figure arranged near one end of the alley and having a receptacle to receive a ball and adapted to discharge the same upon the alley, an inclined runway to feed the ball to the 75 receptacle of the bowler figure, a magazine for receiving and holding a plurality of balls, a chute receiving the balls and extending to the runway, an ejector operating within the chute, means operated by the 80 ball fed upon the alley for operating the ejector, and a pin setter figure arranged near the chute and embodying a movable part connected with the ejector to be operated thereby.

85 5. A toy of the character described, comprising an alley, elements arranged upon the alley to be struck by a ball traveling thereon, a bowler figure arranged near one end of the alley and having a pivoted part 90 provided with a receptacle, a runway extending longitudinally of the alley to feed the ball to said receptacle, a magazine for holding a plurality of balls, a chute receiving the balls from the magazine and extending to the runway, an ejector operating within the chute, and a pivoted lever 95 connected with the ejector and having one end thereof arranged to contact with the ball passing from the alley.

100 6. A toy of the character described, comprising an alley, elements arranged upon the alley to be struck by a ball traveling thereon, a depending chamber arranged near one end of the alley and having an opening, a pivoted lever disposed near and beneath the chamber and having a pocket to receive the ball passing through the opening of the chamber, an upstanding chute, a runway to receive the balls from the chute, an 105 ejector operating within the chute, means connecting the ejector and lever, and a bowler figure receiving the balls from the chute and discharging the same upon the alley.

110 7. A toy of the character described, comprising an alley, an inclined runway extending longitudinally thereof, means for receiving balls from the runway and discharging the same upon the alley, an upstanding chute extending to the runway, an inclined magazine for receiving balls and supplying them to the chute, an ejector operating within the chute, and a lever pivotally connected with the ejector and arranged to be struck by the balls discharging from the alley.

115 8. A toy of the character described, comprising an alley, an inclined runway extending longitudinally thereof, a device to re- 120

ceive balls from the lower end of the runway and discharge the same from the alley, a vertical chute to conduct balls to the runway, an inclined magazine to feed the balls into the chute, an ejector operating within the chute, means to operate the ejector including an element struck by balls discharging from the alley, and a pin setter figure having a movable part connected with the 10 ejector to be operated thereby.

9. A toy of the character described, comprising an alley, means to supply balls to the same including a runway, means to feed

balls to the runway including a magazine for receiving a plurality of the balls and a 15 movable element, and a pin setter figure having a vertically movable limb connected with the movable element to be shifted thereby.

In testimony whereof I affix my signature 20 in presence of two witnesses.
